PRESSING AND STEAMING SADIRO

Albert Tisnerat, Corona, and Max Coonen, Long Beach, Calif.

Application October 24, 1938, Serial No. 236,708

1 Claim. (Cl. 38—77)

This invention relates generally to improvements in electrical sadirons, and the invention has reference more particularly to improvements in electric sadirons provided with means to eject steam from its pressing face to dampen the goods which are undergoing pressing operations.

The prime object of our invention is to provide a novel steam super-heating means in an electric sadiron so that the ejected steam is dry and no drops of moisture can fall on the material which is being pressed to spot or injure the same.

Still another object of our invention is to provide a novel construction in a pressing sadiron, including an integrally formed sole plate and heating lugs.

Other objects, advantages and features of invention may appear from the accompanying drawing, the subjoined detailed description and the appended claim.

In the drawing:

Figure 1 is a side elevation of our sadiron.

Figure 2 is a top plan view of the sole plate and integrally formed heating lugs.

Figure 3 is a sectional view taken on line 3—3 of Figure 1.

Figure 4 is a sectional view taken on line 4—4 of Figure 1.

Figure 5 is a sectional view taken on line 5—5 of Figure 2.

Figure 6 is a fragmentary sectional view taken on line 6—6 of Figure 7.

Figure 7 is a fragmentary bottom plan view of the sole plate.

Referring more particularly to the drawing, the numeral 1 indicates the body of our sadiron, which includes a sole plate 2 and a pair of longitudinally extending heating lugs 3, 4, which are spaced transversely of the iron, substantially as shown in Figures 2 and 5. The reason for spacing the lugs 3 and 4 is to enable the heating elements to more quickly heat the sole plate and have greater efficiency, since a smaller mass of metal above the sole plate must be heated. A cover plate 5 is removably mounted on the body 1 in the usual and well-known manner, and this cover plate includes the usual handle 6, by means of which the sadiron is operated. A heating element 7, preferably of the cartridge type and known as a "Calrod" heater in the trade, extends longitudinally through the lugs 3 and 4. 50

These heating units extend through the rear of the lugs 3 and 4, and the electrical conduit wires are attached to these heating units in the usual and well-known manner.

5 Steam is introduced into the iron through a pipe 8, and the flow of steam is controlled by a valve 9 of usual and well-known construction. The steam after entering through the pipe 8 passes into a substantially V-shaped super-heating duct 10. This duct is drilled in the lugs 3, 4 and is adjacent the electrical heating unit 7. Thus, the incoming steam is reheated or super-heated to prevent condensation. After the steam traverses the duct 10, it passes downwardly at the 10 rear of the iron through the passage 11, into the distributing duct 12. The duct 12 is drilled in the sole plate 2 and is arranged substantially in a V, as shown at 13, at the forward or point end of the iron. A plurality of outlet ports 14 are 15 drilled from the bottom face of the sole plate 2 into the distributing duct 12. These ducts are drilled at an angle towards the inner portion of the sole plate so that steam is ejected inwardly and under the sole plate, thereby more effectively dampening the material which is being pressed. The ports 14 are drilled into the V portion 13 of the distributing duct, so that the rear portion of the sole plate then passes over the dampened area to more effectively press the material. 20

Having described our invention, we claim:

In an electrical sadiron comprising a body, said body including a sole plate and upstanding lugs integrally formed with the sole plate, and extending longitudinally thereof, an electrical heating element in each of the upstanding lugs, and extending longitudinally thereof, said upstanding lugs having super heating ducts formed therein, the super heating ducts being arranged 25 adjacent the heating elements and parallel thereto, said sole plate having a distributing duct arranged therein, means to supply one of said super heating ducts with steam, and conduit 30 means to conduct the super heated steam to said distributing duct, said sole plate having a plurality of outlet ports extending therethrough into the distributing duct.

ALBERT TISNERAT.
MAX COONEN.
